(57) **CLAIM**

The ornamental design for a card reader, as shown and described.

DESCRIPTION

FIG. 1 is a perspective view of a card reader, according to a first embodiment;

FIG. 2 is a side view of the card reader;

FIG. 3 is another side view thereof;

FIG. 4 is another side view thereof;

FIG. 5 is another side view thereof;

FIG. 6 is a top-down view of the card reader;

FIG. 7 is a bottom-up view thereof;

FIG. 8 is a perspective view of a card reader, according to a second embodiment;

FIG. 9 is a side view of the card reader;

FIG. 10 is another side view thereof;

FIG. 11 is another side view thereof;

FIG. 12 is another side view thereof;

FIG. 13 is a top-down view of the card reader; and,

FIG. 14 is a bottom-up view thereof.

The broken lines illustrate portions of the card reader and form no part of the claimed design.

1 Claim, 14 Drawing Sheets
